DESIGN FOR A STRETCHER

Hugh B. Johnson, Rochester, N. Y.

Application August 26, 1942, Serial No. 108,041

Term of patent 3½ years

To all whom it may concern:

Be it known that I, Hugh B. Johnson, an employee of the United States Government, a citizen of the United States, residing at Rochester, in the county of Monroe and State of New York, have invented a new, original, and ornamental Design for a Stretcher, of which the following is a specification, reference being had to the accompanying drawing, forming part thereof,

Fig. 1 is a perspective view of a stretcher, showing my new design; and

Fig. 2 is a side elevational view thereof.

I claim:

The ornamental design for a stretcher, as shown.

HUGH B. JOHNSON,
